UNITED STATES PATENT OFFICE.

DANIEL E. MORAN, OF MENDHAM, NEW JERSEY.

CONSTRUCTION AND SINKING OF CAISSENS OR THE LIKE.

No. 833,792.

Specification of Letters Patent.

Patented Oct. 23, 1906.

Application filed June 23, 1906. Serial No. 323,004.

To all whom it may concern:

Be it known that I, DANIEL E. MORAN, a citizen of the United States, residing at Mendham, in the county of Morris and State of New Jersey, have invented certain new and useful Improvements in the Construction and Sinking of Caissons or the Like, of which the following is a specification.

In my application for patent, Serial No. 321,845, filed June 15, 1906, I have described and claimed generically the reinforcing of a concrete caisson with metal, preferably forming a continuous connection between the superimposed load and the subfoundation.

The present invention provides a construction which is within the broad invention there described, but is substantially different from the specific embodiment upon which said application is based. The present case involves also a departure in that steel is introduced in the form of a column which may and preferably does provide the principal strength, the concrete serving, primarily, as a casing for the steel column and as a means for erecting the same in the desired position.

The methods of introducing or erecting the steel column may be classified under two heads. First, the column can be embedded in the solid concrete of the pier and the whole sunk as a unit. In this case the column can extend down through the roof to within a few inches of the level of the cutting edge, and after the caisson has reached its final position the supporting effect of the column can be transmitted to the rock subfoundation by a metal underpinning inserted by men in the working chamber. In this case the final adjustment of the length of the column would be at the base. In the second method it would be necessary to leave a vertical opening through the body of the caisson, either the shaft-opening or a special opening for the purpose. After the caisson has reached its final position the column can be lowered to the rock and the adjustment in length be made at the top. This second method has the advantage that the steel columns can be exactly located and accurately plumbed, even if the caisson goes somewhat out of level or out of position, as sometimes happens.

Referring to the embodiments of the invention illustrated, Figure 1 is a vertical section through a caisson at the shaft-opening, the caisson being sunk to the desired depth. Fig. 2 is a similar section showing a column erected

through the shaft. Fig. 3 is a similar section showing the filling of concrete introduced about the column. Fig. 4 is a horizontal section approximately on the line 4-4 in Fig. 3. Fig. 5 is a vertical section, and Fig. 6 a section on the line 6-6 in Fig. 5 illustrating another method.

The caisson may be of any suitable shape. The body of concrete is represented at A, below which is the working chamber B, having sides C and a cutting edge D, and through the body passes a shaft E. The caisson is usually sunk to within a short distance of the rock subfoundation F. After sinking such a caisson in the usual way the rock will be leveled and a pedestal G set up approximately in line with the center of the shaft E. The pedestal may be lowered in sections and bolted together by the men in the working chamber, if too large to pass through the shaft, or placed in the chamber prior to sinking and carried down with the caisson. The column H is then erected length by length within the shaft, the workmen filling in behind them with concrete as they withdraw from the chamber and up the shaft. The column may be of any one of a great variety of designs. The design and material are not important to this invention. I have shown a composite column made up of Z-bars, so as to facilitate the entrance of the concrete into contact with all parts of the metal to protect the same from rust. The lining J of the shaft may be left in place as is usual, or it may be withdrawn in the manner covered in the application of myself and John W. Doty, Serial No. 309,850.

Since the column H, of metal, is the principal supporting member and the prime function of the concrete is to protect the column, caissons of this type will generally be of comparatively small cross-section, as shown in Fig. 4, and may be sunk very rapidly and at slight expense. It is to be observed, however, that the concrete, though primarily a protector for the metal column, yet braces the latter considerably against buckling and may even be arranged to take a part of the load. The shaft-lining J around the column also adds considerably to its resistance to buckling.

A second method of construction is shown in Figs. 5 and 6. In this case a column H' is supported in the concrete body A and embedded firmly therein at one side of the shaft E. The column H' may be very easily provided for by the molding up of the body A of

the caisson before sinking in the manner described in an application of myself and John W. Doty, Serial No. 276,767, the length of the column being continually added to in advance of the height of the concrete. Any number of columns may be carried in the body of the caisson in this manner. The drawings show only one shaft E and one column H, any remaining portions of the caisson being removed. After the caisson is sunk to the desired depth any suitable underpinning K may be provided for transmitting the supporting action of the column to the rock F. The column is preferably put under a slight initial strain in this way. The shaft E in this case may also be used for an additional column H, as shown, and any number of such shafts may be provided either with or without the lining J. It will be observed that according to both methods described the continuous column connecting the superimposed load to the subfoundation is formed after the caisson is sunk, the column being finished in one case at the bottom and in the other case at the top end. The filling of concrete may be introduced through one or more pipes K, which are withdrawn as the filled level rises. In my Patents Nos. 830,515 and 830,516, dated September 11, 1906, I have described the introduction of metal reinforces in a manner identical with the manner of introducing the column herein and have made broad claims covering both inventions. Though I have described with great particularity of detail certain specific embodiments

of the invention, yet it is not to be understood therefrom that the invention is restricted to the particular embodiments disclosed. Various modifications thereof in detail and in the arrangement and combination of the parts may be made by those skilled in the art without departure from the invention.

What I claim is—

1. The method which consists in sinking a caisson, and erecting a metal column within said caisson extending continuously from the subfoundation to the top of the caisson, and subsequently inclosing said column in an envelope of concrete.

2. The method which consists in sinking a caisson, and erecting a metal column upon the subfoundation and passing it through the shaft of the caisson.

3. The method which consists in sinking a caisson having a concrete body with a metal column embedded therein and projecting into the working chamber, and subsequently inserting a metal underpinning between the base of said column and the subfoundation.

4. The combination with a caisson, of a metal column supported on the subfoundation and extending upward through the caisson.

In witness whereof I have hereunto signed my name in the presence of two subscribing witnesses,

DANIEL E. MORAN.

Witnesses:

DOMINGO A. USINA,
THEODORE T. SNELL.
